UNITED STATES PATENT OFFICE.

WALTER O. AMSLER, OF PITTSBURGH, PENNSYLVANIA.

ANNEALING FURNACE AND LEER.

Application filed June 3, 1921. Serial No. 474,691.

To all whom it may concern:

Be it known that I, WALTER O. AMSLER, a citizen of the United States, residing at Pittsburgh, in the county of Allegheny and 5 State of Pennsylvania, have invented certain new and useful Improvements in Annealing Furnaces and Leers, of which the following is a specification.

This invention relates to an annealing 10 oven or leer for treating glassware, and particularly to a leer having an arrangement of flues therein for effecting the proper distribution of heat.

In leers of this type there is usually provided a relatively short heating chamber 15 which is maintained at a relatively high temperature, and a tunnel-like structure communicating therewith. The temperature of the tunnel is graduated so that the discharge end most remote from the heating chamber is relatively cool.

The glassware is introduced at the end of the heating chamber opposite the tunnel. It is desirable that the glassware be moved 25 immediately into a temperature sufficiently high to relieve all internal stress in the glass articles. Owing to the fact that the end of the heating chamber into which the articles are introduced is usually open, the temperature 30 at the point of introduction is considerably lower than the desired temperature.

Furthermore, because it has usually been the practice to deposit the articles in a row 35 on a stationary shelf at one end of the leer and push the row forwardly onto a conveyor, the articles remained for some time at the point of introduction where the heat was not sufficient to prevent cracking and breaking 40 of the articles.

It is an object of the present invention to provide a heating chamber and a combustion chamber with an interposed muffle in which the end of the heating chamber at which the 45 articles are introduced may be maintained at a high temperature.

Further objects of the invention are to provide a leer in which the end of the heating chamber is closed, the portion of the 50 wall closing the end preferably providing a flue for the circulation of heated gases about the extreme end of the heating chamber; and to provide means whereby the articles may be introduced into the heating chamber 55 at one end thereof through the side.

My invention may be understood by refer-

ence to the accompanying drawings, in which:

Fig. 1 is a vertical longitudinal section through a portion of a leer embodying my 60 invention, and with a portion of the interior wall broken away to show the arrangement of some of the flues;

Fig. 2 is a vertical section on line II—II of Fig. 1; and

Fig. 3 is a horizontal section through the leer shown in Fig. 1, a portion of the section being above the leer conveyor and a portion below the level of the leer conveyor.

In the drawings, A represents broadly the 70 heating chamber; B is the tunnel; C, an endless conveyor having the receiving end thereof supported on wheels or a roller D.

The heating chamber has an outside wall 5 and an arched inner wall or muffle 6. The 75 top of the muffle, which is preferably made of pannelled tile, as shown, is spaced from the top of the outer wall, while the downwardly extending sides 7 of the muffle are formed of tile or blocks having channels 80 therein, as shown in Fig. 2, the sides of the channels contacting with the wall 5 to form a plurality of vertically extending side flues 8. At 9 is a partition extending across the space formed between the wall 5 and the 85 wall 6 to divide the space into a combustion chamber 10 and an exhaust chamber 11, the length of the former being much greater than the length of the latter.

Beneath the conveyor C is a tile floor 12 90 supported above the bottom wall 13 of the heating chamber. Transverse walls 14 and 15 serve to close the front and rear ends, respectively, of the space 16 between the floor 12 and bottom wall 13. The flues 8 terminate 95 in and open into space 16, at 8^a and 8^b, as shown in Fig. 3.

Projecting transversely from the sides 5, part way across the space 16 and opposite each other, are baffle walls 17, one of which 100 is clearly shown in Fig. 3. At the end of the wall 17 is a longitudinally extending wall 18, and parallel thereto, but spaced therefrom in order to form longitudinal flues, are partitions 19. At 20 and 21 are 105 relatively small sections of partitions for forming a series of short flues. At 22 and 23 are other walls for forming similar flues.

As clearly shown in Fig. 1, the side walls of the muffle adjacent the roller D are not 110 full length and hence the flues 8 in this portion of the wall do not communicate directly

with the space 16, but, as shown in the broken away portion of Fig. 1, the various flues communicate at this point through passages 8^c with flue 8^d.

5 The end wall of the leer is indicated at 24, and has an opening 25 therein in which may, through a door 25', be operated a pusher, not shown, for moving the articles onto the conveyor after they have been moved into 10 the heating chamber, as hereinafter described. The end wall serves to close the combustion chamber and the upper portion of the muffle chamber, but does not extend throughout the height of the leer, its lower

15 end terminating above the base of the construction. At 26 is a horizontal wall at the bottom of the end wall 24, and at 27 is a portion of the bottom of the muffle chamber. A transversely extending flue 28 is provided 20 by this construction, which flue connects with the last of the vertical flues 8 at each side of the leer, as clearly shown in Fig. 3.

At 29 is a vertical flue communicating with flue 28 and with the forwardly extending underground flue 30. The forward end of the flue 30 communicates with a transverse underground flue 31 which, through vertical conduits 32, communicate with one of the vertical flues 8 that terminate at 8^b at each side of the heating chamber. A damper is preferably provided in flue 29 at 29^a. Those of the flues 8 which terminate at 8^b communicate with exhaust chamber 11. Supported on the top of the 30 oven over the chamber 11, with which it communicates, is a chimney 33, in which are preferably placed dampers 34.

Near the rear end of the top of the combustion chamber 10 is a burner or supply 35 pipe for heated or combustible gases, 35.

In the side walls of the heating chamber at 36 are openings through which the articles of glassware are introduced on a conveyor or chute 37. From the conveyor 37, 40 the articles are pushed forwardly onto shelf 38, and from there onto the conveyor C.

In operation, combustion is effected in the chamber 10. The burner 35, being near the rear of the heating chamber, most of the 45 heated gases go down those of the flues 8 nearest the receiving end of the leer, and through the passages 8^c, flue 8^d, and into the chamber 16. These gases pass transversely across chamber 16 along the rear 50 wall thereof, then forwardly along the central longitudinal flues in chamber 16, and at the forward end of the chamber are deflected rearwardly into the pockets formed at the front sides of baffle walls 17, and into 55 the vertical flues 8 at 8^b. Thus, they heat most intensely the portion of the muffle chamber at the top, sides and bottom over the receiving end of the conveyor, especially 60 the portion adjacent the supporting wheels D.

Some of the gases in chamber 16 go down other of the flues 8 which are further forward, and emerge into chamber 16 at 8^a, where, by reason of the baffles 17, they circulate to heat the bottom of the muffle chamber near the sides of the oven, and then pass into the longitudinal flues to mingle with the other gases. The gases passing down the rearmost flue 8 at each side of the heating chamber into flue 8, heat the end of 70 the heating chamber. Then they pass down flue 29 through flues 30, 31 and 32 to mingle with the other gases, which all pass up into chamber 11 and out the chimney 28.

This arrangement of flues causes the receiving end of the heating or muffle chamber to be most intensely heated and to be maintained at a sufficiently high degree of temperature to overcome the internal stress of the articles of glassware as they are introduced. It also provides for a gradual reduction in the temperature from the receiving end forwardly to the tunnel B.

What I claim is:

1. A heating chamber for leers comprising an outer wall, an inner wall enclosing a muffle chamber, said inner wall being spaced from the outer wall at the top and bottom, vertical flues at the sides of the inner wall communicating with the spaces above and below the muffle chamber, a partition dividing the upper space into a combustion chamber and an exhaust chamber, baffle walls arranged longitudinally in the space below the muffle chamber along the central portion thereof and of less length than the muffle chamber, transverse baffles in the space extending from the sides inwardly between the vertical side flues which communicate with the combustion chamber and those which communicate with the exhaust chamber.

2. A heating chamber for leers comprising an outer wall, an inner wall enclosing a muffle chamber, said inner wall being spaced from the outer wall at the top and bottom, vertical flues at the sides of the inner wall communicating with the spaces above and below the muffle chamber, a partition dividing the upper space into a combustion chamber and an exhaust chamber, and baffles arranged in the space below the muffle chamber for directing some of the gases coming through some of the vertical flues communicating with the combustion chamber rearwardly and then forwardly, and then rearwardly to those of the vertical flues which communicate with the exhaust chamber.

3. A heating chamber for leers comprising an outer wall, an inner wall, which inner wall encloses a muffle chamber, means for circulating heated gases between the inner and outer walls, means for introducing articles at the side of the muffle chamber, and

means for circulating the heated gases around the muffle chamber to the rear of the point where the articles are introduced into the muffle chamber.

5 4. A heating chamber for leers comprising an outer wall, an inner wall enclosing a muffle chamber, an endless conveyor in the chamber, supporting wheels for the conveyor extending into the muffle chamber, 10 vertical side flues for circulating heated gases between the outer and inner walls, and passages connecting those of the side flues adjacent the wheels whereby the portion of the muffle chamber into which the wheels extend 15 may be heated by circulating gases thereabout.

5. A heating chamber for leers comprising an outer wall, an inner wall enclosing a muffle chamber, an endless conveyor in the 20 chamber, wheels in the chamber at one end thereof for supporting the conveyor, a chamber formed above and below the muffle chamber between the walls, the upper chamber extending rearwardly over the wheels while said lower chamber extends only to the wheels, vertical flues between the walls communicating with the upper and lower chambers, the vertical flues adjacent the wheels not opening into said lower chamber, and a passage connecting the lower 30 ends of those flues adjacent the wheels with a flue communicating with the lower chamber so that the portion of the muffle chamber adjacent the wheels may be heated.

35 6. A heating chamber for leers comprising an outer wall, an inner wall enclosing a muffle chamber, an endless conveyor in the chamber, wheels in the chamber at one end thereof for supporting the conveyor, a chamber formed above and below the muffle chamber between the walls, the upper chamber extending rearwardly over the wheels while said lower chamber extends only to the 40 wheels, vertical flues between the walls communicating with the upper and lower chambers, the vertical flues adjacent the wheels not opening into said lower chamber, and a 45 passage connecting the lower ends of those

flues adjacent the wheels with a flue communicating with the lower chamber so that 50 the portion of the muffle chamber adjacent the wheels may be heated, and means for heating the muffle chamber to the rear of the wheels.

7. A heating chamber for leers comprising 55 an outer wall, an inner wall enclosing a muffle chamber, an endless conveyor in the chamber, supporting wheels for the conveyor near one end of the muffle chamber, a chamber above and below the muffle chamber 60 and between the outer and inner walls, flues between the walls communicating with the upper and lower chambers, means for heating 65 the portion of the walls adjacent the supporting wheels, and means for heating the portion of the muffle chamber to the rear of the wheels.

8. In an annealing furnace, the combination of an annealing chamber, a carrier for articles to be annealed consisting of an endless belt carried on a drive wheel, the said drive wheel being arranged beneath and extending through an opening in the floor of and into said annealing chamber; and the side walls and roof of the annealing chamber 70 overhanging said drive wheel, the belt of the carrier from its point of tangency with its drive wheel extending wholly within the annealing chamber, and a muffle chamber 75 enveloping the walls of the annealing chamber and enveloping the overhanging portion of the roof and side walls of the annealing chamber.

9. In an annealing furnace, a leer chamber having a carrier for the articles to be treated and a sprocket-wheel for the carrier located outside its entrance end, main side flues for the leer chamber, and a supplemental flue contiguous to the sprocket wheel and communicating with one of said main flues. 85 90

In testimony whereof I affix my signature in presence of two witnesses.
